UNITED STATES PATENT OFFICE.

HERMAN JOSEPH FLEDDERMAN, OF TULSA, OKLAHOMA.

INTERNAL-COMBUSTION ENGINE.

Application filed August 25, 1920. Serial No. 406,002.

To all whom it may concern:

Be it known that I, HERMAN JOSEPH FLEDDERMAN, a citizen of the United States, and a resident of Tulsa, in the county of Tulsa and State of Oklahoma, have invented certain new and useful Improvements in Internal-Combustion Engines, of which the following is a specification.

My invention is an improvement in internal combustion engines, and has for its object to provide an engine of the character specified, having combustion chambers at each end of the cylinder, together with means for supplying fuel to the said ends, and for permitting the waste products to exhaust, the inlet and the exhaust ports being controlled by sleeve valves, mounted to reciprocate, and controlled by the movement of the piston, each end of the cylinder having igniting devices.

In the drawings,

Figure 1 is a vertical section of one cylinder of the improved motor,

Figure 2 is a front view of the valve sleeves,

Figure 3 is a horizontal section through the cylinder and associated elements.

Figure 4 is a diagrammatic view showing the gear connection between the valve controlling mechanism and the crank shaft.

In the present embodiment of the invention, the engine frame casting 1 rests upon the upper member 2 of the crank case, the said case consisting of the upper member 2 and the lower member 3. A cylinder 4 is arranged within the engine frame casting, and a piston 5 moves within the cylinder. As shown, the cylinder is jacketed, the jacket being indicated at 6, and being provided for the circulation of a cooling fluid, and at the upper end the jacket and the cylinder are closed by a head 7-8, the portion 7 of the head closing the engine frame casting while the portion 8 closes the end of the cylinder. This head has a central threaded opening for engagement by a spark plug 9, and a second plug 10 is engaged with the engine frame casting at the lower end of the cylinder, the said plugs extending in to the cylinder.

The piston 5 has the usual packing rings, and it is connected by a rod 11 with a cross-head 12, which moves in a guide 13. The piston rod, as clearly shown in Figure 1, is threaded through an axial opening in the piston, and is engaged by a nut 14 above the

piston. At its lower end, the rod engages a threaded recess in the crosshead, and is locked by a nut 15. A connecting rod 16 connects the cross-head with a crank 17 of the crank shaft indicated at 18, the said shaft being journaled in bearings 19 in the crank casing. At the lower end of the cylinder, the rod passes through a stuffing box 20 of usual construction, and the connecting rod is connected to the crank by a sectional bearing 21.

As illustrated in Figure 1 the cross head 12 is in the form of an inverted cup and is gradually decreased in diameter toward its forward end to provide a baffle whereby the oil is confined in the lower portion of the engine.

The cylinder has intake ports 22 and 22^a, and exhaust ports 23 and 23^a, at its upper and lower ends, and these ports are in register with other ports 24, and 24^a, and 25 and 25^a in the frame casting. Valve sleeves 26 and 27 are arranged in the space between the cylinder and the engine frame casting, the said sleeves being concentric, and fitting one within the other, and the sleeve 27 is the inner sleeve. These sleeves have ports for placing the ports 22-24, 22^a and 24^a, 23-25, 23^a and 25^a, in communication, and the sleeves are controlled by an eccentric shaft 29, which is journaled in the crank case at one side of the crank shaft and parallel therewith. This eccentric shaft has 2 crank arms 30 and 30^a, and these arms are connected by links 31 and 31^a, with the valve sleeves 27 and 28 respectively. The cranks 30 and 30^a are arranged at angles of 120 degrees with respect to each other, and the eccentric shaft is journaled in suitable bearings 33.

As clearly shown in Figure 1, the piston 5 is hollow, being an annular chamber for lubricant, and this chamber communicates with longitudinally extending passages 34 and 34^a in the piston rod, by means of lateral passages 35. The passage 34 communicates at its lower end with the interior of the cross-head guide, and the passage 34^a communicates at its lower end with an axial passage 23 in the crank shaft and in the cranks. This passage 36 extends longitudinally of the crank shaft, and passes outwardly through each crank, and a continuation passes from the crank pin through the cross-head to the passage 34^a.

A system for lubricating and cooling oil,

indicated at 37, communicates with the axial passage and the crank shaft by means of a passage 38, and by means of a passage 39 with a similar passage in the cam shaft 29, 5 so that all of the parts are thoroughly cooled and lubricated from the system. The cam shaft is driven from the crank shaft by means of a pinion 59 on the crank shaft, and a gear wheel 40 on the cam shaft, the 10 gears 39 and 40 constituting a reducing gear.

The operation of the motor, which is a double acting motor, having explosion chambers on both sides of the piston, is as 15 follows:—When the piston moves outwardly, a charge is drawn into the upper end of the cylinder, while that already drawn into the lower end is compressed, the valves 26 and 27 admitting the charge to 20 the upper end during this movement, while they are closed at the lower end. The charge at the lower end is compressed, and as the piston reaches the end of its downward stroke, the charge is ignited. The 25 piston is driven outward, and the charge at the outer end is compressed, the ports at the outer end being closed at this time. The ports at the inner end are now open, and as the charge at the outer end is ignited, the 30 piston is driven inward, driving out the exhaust products at the inner end of the cylinder, the exhaust valve being open at this time. When the piston returns outward, the exhaust ports 23 and 25 are open, 35 and the exhaust gases at the outer end of the cylinder are driven out. Meanwhile a charge is being drawn into the inner end of the cylinder, the ports 22^a and 24^a being

open, and as the piston moves inward, this charge is compressed. At this time the 40 ports 22 and 24 are open, while the ports 23 and 25 are closed, and the moving inward of the piston draws a charge into the outer end of the cylinder. Thus in each 45 cycle of the engine a charge is drawn into each end of the cylinder, compressed and ignited, and the exhaust gas is driven out of both ends of the cylinder.

I claim:—

1. An internal combustion engine comprising a cylinder, a piston therein, a rod rigidly secured to said piston, the lower end of said cylinder being provided with means providing a gas tight connection between the lower end of the cylinder and said rod, a cross head in the form of an inverted cup rigidly secured to the lower end of said rod and gradually and uniformly decreased in diameter toward its upper end to form an oil baffle, a tubular 60 guide depending from the lower end of said cylinder and receiving said cross head, and a connecting rod secured to said cross head.

2. In an internal combustion engine, a cross head comprising a body in the form 65 of a cup having its upper side formed with means whereby the same may be connected to the lower end of a piston rod, and means arranged within the body for connecting the body to the rod of a crank shaft, said body being interiorly and exteriorly decreased in diameter toward its upper end to 70 form an oil baffle, said body being adapted to operate within a tubular guide.

HERMAN JOSEPH FLEDDERMAN.
